SPRINGLESS SELF-CLOSING DOOR

John A. Janson, East Sparta, Ohio

Application September 4, 1937, Serial No. 162,478

3 Claims.

(CL. 20—16)

The present invention relates to closures and supporting and operating means therefor, and has reference in particular to a simple two-way closing, vertically disposed, hingedly mounted door, and the chief purpose of the invention is to provide a structure of this type which is devoid of springs or equivalent devices and to substitute in lieu thereof gravity actuatable means for closing, centering and maintaining the door normally closed.

In reducing to practice the principles of the specific conception in mind, I have found it expedient and practicable to employ a hingedly mounted, bodily liftable door whose lower end is cooperable with ball castor and track means, and whose upper end is associated with a novel structure permitting the rise and fall of the door while constantly maintaining a closure between the door and adjacent part of the surrounding frame structure.

As implied by the preceding statement, the novelty resides primarily in the ingenious adapter structure between the upper edge of the door and the frame structure, which adapter is automatically raised by the lift of the door and is gravity lowered so that as the door comes to its normal centered and closed position, said adapter means maintains a definite closure between the door and frame.

Other features and advantages will become more readily apparent from the following description and accompanying illustrative drawings.

In the drawings:

Figure 1 is an elevational view of a door, frame, and associated structure forming the novelty of the present invention, the door being shown in its normal centralized closed position.

Figure 2 is a top plan view with the top part of the frame structure removed to expose the underlying details.

Figure 3 is a fragmentary view in section and elevation disclosing the upper ends of the frame and door and associated structure.

Figure 4 is a fragmentary view based on Figure 3 and showing the opposite or lower end construction and arrangement of features.

Figure 5 is a vertical section which may be said to be on the approximate plane of the line 5—5 of Figure 3.

Figure 6 is a horizontal view on the plane of the line 6—6 of Figure 3.

Figure 7 is a view taken on the general plane of the line 7—7 of Figure 4 with the door appearing in dotted line.

Figure 8 is a bottom edge view of the door.

Figure 9 is an end view of the hinged upper end portion of said door.

Reference being had now to the drawings, it will be observed that the door, which is of any appropriate material, is denoted by the numeral 10 and is associated with the surrounding frame structure 11 including vertical hollow stiles or casings 12 and a topping horizontally disposed head or casing structure 13. As shown in Figure 5, the lower or bottom wall 14 of the head 10 casing 13 is provided with a longitudinally elongated slot to accommodate the projectible and retractile trough-like adapter and closing unit 15. To be more specific, this part 15 is channel-shaped in cross-sectional form with its side walls 15 slidable through the slots formed in the part 14. Said part 15 functions as a closure to maintain a constant closing action between the upper end of the door and the horizontal casing 13 of the frame means 11. At one end and as seen in Figure 3, the bottom portion of the adapter unit 15 has fastened thereto a wear plate 16 provided at its left hand end with a detent hook 17 engaging the projecting end portion of a complementary wear plate 18 on the corresponding upper edge of the door. The door is notched or cut away as indicated at the point 19 to accommodate the interlocking connection between the hook and the overhanging end portion of the complementary wear plate 18.

Attention is now directed to the structure interposed between the floor and the bottom of the door. This comprises an especially designed fixture unitarily denoted by the numeral 20. It is screwed or otherwise secured to the floor and includes a segmental base plate 21 having a vertical stabilizing and attaching upstanding rim portion 22. The rim portion merges into duplicate segmental risers or tracks 23 disposed on opposite sides of the door in the proper path of swing of 40 said door. The door is provided with a wear plate 24 and with a cup or receptacle 25 to accommodate the castor roller or ball 26. This provides a tracking element and is ridable on the track flanges 23. Inasmuch as the flanges are tapered 45 to the degree shown, they are in effect cam elements of proper segmental form to allow the door to rise and fall as its swings to open and closed position. That portion of the base plate 21 between the adjacent ends of the so-called tracking 50 cams 23 is preferably formed with a keeper recess forming a receiving pocket 27 to accommodate the ball 26 in its normal resting position, in which position the door is then closed.

Attention now comes to the hinge rod or pintle 55

28, this being located in a bore in the door having its lower end fixedly attached to the base plate 21. The upper end is saddled in the eye portion 29 of the adapter bracket 30. An appropriate fastening 31 secures together the complementary portions of said bracket and serves to bind the hinge rod or pintle 28 rigidly in place. Thus, we have a perpendicular fixed rod 28 secured to the fixture 26 and the bracket 30 and parallel to the adjacent casing 12 of the door frame. The door itself swings freely on this rod as a pivot.

In operation as the door is swung in either direction, it is obvious that the anti-friction ball 15 26 rides on the tracking cam 23 on either side. As the door swings to open position it begins to rise bodily. In so doing it exerts an upward thrust on the telescoping or receding closure unit 16. Said unit is retracted into the hollow casing 20 member 13 of the door frame. When the door again resumes closed position, the adapter unit 16 gravitates to its normal closing position. Consequently, said unit 16 is self accommodating and makes it possible to utilize a structure of 25 this type eliminating the employment of springs and other devices likely to get out of order.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within 35 the field of invention claimed may be resorted to if desired.

I claim:

1. In a structure of the class described, in combination, a door frame, a door hingedly 40 mounted in said frame, means interposed between the door and floor for bodily raising and

lowering the door as it swings from closed to open position, together with means for maintaining a constant closure between the upper portion of the frame and adjacent upper end portion of the door, said means embodying a receding gravity lowered shield interconnected with the door for raising and lowering movement therewith as a unit.

2. In a construction of the class described, in combination, a relatively stationary door frame, 10 a door hingedly mounted for swinging in a horizontal direction on a vertical pivot, means interposed between the bottom of the door and adjacent floor for automatically closing the door, said means serving to bodily raise and lower the 15 door as it swings to and fro, an adapter unit interposed between the upper portion of the frame and upper edge of the door and interconnected with the door for raising and lowering movement therewith, said adapter unit being 20 telescopically mounted to permit desired projectible and retractible action thereof.

3. In a construction of the class described, in combination, a relatively stationary door frame, a door hingedly mounted for swinging in 25 a horizontal direction on a vertical pivot, means interposed between the bottom of the door and adjacent floor for automatically closing the door, said means serving to bodily raise and lower the door as it swings to and fro, an adapter unit 30 interposed between the upper portion of the frame and upper edge of the door, said adapter unit being telescopically mounted to permit desired projectible and retractible action thereof, together with wear plates interposed between 35 the adapter and upper edge of the door, said wear plates being interlocked at corresponding ends to cause a raising and lowering movement thereof as a unit.

JOHN A. JANSON. 40
